Frank J. Stefe, Milwaukee, Wis., assignor to Safway Steel
Products, Inc., Milwaukee, Wis., a corporation of Wisconsin

Filed Apr. 18, 1963, Ser. No. 74,502

Term of patent 14 years

(Cl. D34—5)

FIG. 1 is a perspective view of the playground apparatus in the form of a fanciful alligator showing my new design;

FIG. 2 is a side elevation of the apparatus; and

FIG. 3 is a top plan view of the apparatus.

The reverse side of FIG. 2 is substantially the same in appearance.

I claim:

The ornamental design for playground apparatus in the form of a fanciful alligator, as shown and described.
